UNITED STATES PATENT OFFICE.

FREDERIC W. HILLARD, OF TOTTENVILLE, NEW YORK.

TYPE-WRITING MACHINE.

No. 923,120.

Specification of Letters Patent.

Patented May 25, 1909.

Original application filed August 25, 1896, Serial No. 603,845. Divided and this application filed November 10, 1904. Serial No. 232,251.

To all whom it may concern:

Be it known that I, FREDERIC W. HILLARD, a resident of Tottenville, in the county of Richmond and city and State of New York, have invented certain new and useful Improvements in Type-Writing Machines, of which the following is a specification.

This application is a continuation and division of my previous application Serial Number 603,845, filed August 25th, 1896, and is filed in pursuance of a requirement of division of the Patent Office.

The invention described and claimed herein relates to the bar mechanism and particularly to a certain grouping of the bars and curvature thereof, whereby space in the type bar rest or basket is greatly economized, and the danger of collisions of the type heads in operating is much reduced.

With the construction shown, the obliquity of the clearance bends of the several type bars varies with the obliquity of the setting of the heads relatively to their own bars and those that they are to clear, and the amplitude of the bends varies with the size and length of the heads (which latter is in a measure, dependent upon the number of type characters on the heads). But while I have thus shown the clearance bends associated with type bars each carrying two or more type characters, it is obvious that such bends may be used irrespective of the number of characters upon each head, whenever the size or shape of the heads and the relation of the parts is such as to render their use advantageous.

In the accompanying drawings which form a part of this specification, Figure 1 is a detail side elevation of my type writing machine, some of the parts being cut away in longitudinal section to more clearly show the mechanism of the machine. Fig. 2 is a side elevation in the same position as Fig. 1 but with all the parts in place, excepting that some details are omitted. Fig. 3 is a detail perspective view of the type bars belonging to the left side of the machine, grouped together as they appear when in place in the type ring. Fig. 4 is a plan view of the machine. Fig. 5 is a protracted view of the type bars on the left hand side of the machine developed from Figs. 3 and 4.

Fig. 1 shows a sectional view of the base frame, 1. Extending in a perpendicular direction from the back portion of the base

frame are the brackets 2 for the carriage guide rail 3 and the parts mounted on the guide rail. The principal parts which are mounted on the guide rail are the paper carriage 4, the rack 5, and the carriage shifting frame 6. At the front of the machine is placed the key board. Intermediate between the paper carriage and the key board the type bar plate 7 is mounted on the base frame of the machine. The type bar plate inclines backward at a slight angle from the perpendicular plane. Fig. 1 shows a sectional view of the type bar plate, taken on the line Y Y of Fig. 4. The type bar plate comprises a ring with type bars mounted concentrically thereon and pivoted in the usual manner so that they can all strike through the central opening in the ring to a common printing center on the platen 8. The type bar plate is inclined slightly backward from the perpendicular in order that the line of vision between the operator on the machine and the printing center may be clear and unobstructed. There is a central opening through the casing 9 which guards the type bar plate. Through this central opening the writing on the platen may be clearly seen by the operator as soon as each letter has been printed.

The type bars 12 are connected with the key levers 17 and are operated when the key levers are depressed. Owing to their positions in the type ring they cannot be connected to the key levers in the ordinary manner by simple connecting wires. The method by which I connect them is as follows: I attach a connecting wire 18 to each type bar in the usual manner. These connecting wires extend in a direction substantially parallel with the direction of the type bars when at rest. At their front ends they are attached to bell crank levers 19. To the other ends of the bell crank levers are attached a second set of connecting wires 20; and these latter wires are extended downwardly and connected with the key levers, in the usual manner.

I have also provided means for keeping the space in front of the printing center on the platen clear of connecting wires so as not to obstruct the view of the writing. In order to accomplish this I provide bell crank levers 19 above the line of writing with elongated rock shafts 21, so as to connect the central type bars 12, above the visual line, with the

key levers 17 at the right hand or left hand side of the key board, depending on the location of the several type bars above the line of writing in place of the bell crank levers. By 5 attaching the connecting wire 18 to the end of the rock shaft directly above the line of vision and the connecting wire 20 to the other end of the rock shaft I remove the connecting wire 20 out of the line of vision between 10 the operator and the platen.

In the type bar plate I have arranged type bars pivoted in two circles concentric with the printing point, the whole set in both circles being aimed to strike at the common printing point. One of the two circles is of 15 smaller radius than the other and hence the type bars pivoted therein are shorter than those in the other circle. By this arrangement it will be seen that longer pivots can be 20 provided for the several type bars than would be possible in case all of the pivots were arranged in a single circle; by this arrangement also it follows that the type heads when in their normal positions will rest, not all 25 in one circle, but in two circles corresponding to the two circles of pivots. Each of the type-bars carries a type head 15 with two type characters, and part of the type bars have type heads with three characters each. 30 The type heads on the bars directly above and below the printing center are in line with their bars. But as the bars are arranged on the sides of the ring as well as above and below the printing center the type heads are 35 placed on the bars more and more obliquely until on the extreme sides of the ring they are placed on the bars at right angles. In rapid work the type heads on the bars pivoted in the one circle and lying intermediate 40 the length of the bars pivoted in the other circle are liable to collide when being driven to the printing point or returning therefrom, with the next adjacent type bar, when the latter is moving in the opposite direction. In order to guard against this danger I have provided clearance bends in the shanks of the type bars pivoted in the larger circle, for the type heads of the bars pivoted 45 in the smaller circle to lie in when at rest and to play through when adjacent type bars are moved in quick succession to and from the printing point. The type bars as shown have their shanks extending in substantially 50 radial lines excepting for the clearance bends in the bars pivoted in the larger circle, which latter bars have bends provided at just the points needed for clearance of the heads on the bars in the smaller circle. The type heads which are set obliquely on their bars 55 on the short bars fit nicely into the double bends on the long bars, because the end of the type head on one side of the long bar is lower down on the bar than is the one on the other side of the long bar.

60 Figs. 3 and 5 show the arrangement of the

bars on one side of the type bar plate, extending from the bar directly below the printing center around the side of the type bar plate and up to the bar directly above the printing center. The longer type bars are shown 70 pivoted farther back than the shorter bars, and provided with the double bends near their type heads for clearance with the type heads on the shorter bars.

The arrangement of the type keys 30 in 75 the key board is that of the Remington Standard Typewriter, excepting that in the next to the top row of keys I have placed a row of double spacing keys 32 which are connected with the type characters which are 80 frequently terminal characters. The row of double spacing keys is distinguished from the remainder of the keys by being black with white letters, while the other keys are 85 white with black letters.

The paper carriage 4, is mounted at its 90 rear edge on the guide rail 3 and is fastened to the rail by grooves in the carriage and corresponding grooves in the guide rail, and bearing balls in the grooves. The carriage is free to travel on the rail on the bearing balls, from one end of the rail to the other, for letter spacing. At its front edge the carriage is provided with the roller 25 which rests and travels with the carriage on the front rail 26. 95 It can be lifted off from the front rail, and the carriage raised for inspection of the writing, etc., by taking hold of the front of the carriage and lifting it. Fig. 1 shows the carriage in its normal position, and Fig. 2 shows 100 it in its raised position. The arrows in Figs. 1 and 2 show the line of vision. When the carriage is raised the guide rail is revolved with the carriage, the two being held together and revolved together on their axes 105 by the bearing balls 27. There are two bearing balls on the top of the guide rail, and one at the bottom of the rail intermediately between the two on the top of the rail. The front carriage rail is also pivoted concentrically with the guide rail 3 and the carriage 4. The front rail is supported by the shifting frame 6. The carriage is shifted from its normal position in lower case to its shifted 110 position in upper case by depressing the shifting frame 6 and the front rail 26. The carriage is also shifted to a third position for printing special characters, which are carried on certain of the type bars, by lifting the front rail. The shift key 28 is connected 115 with the shift frame 6 by means of the link 29. The carriage is held in its normal position against gravity by means of a spring mechanism not shown. When it is desired to lift the shifting frame and the carriage to 120 their upper position another spring mechanism assists in overcoming the weight of the carriage. Hence the carriage can be easily lifted to shift it to special case. The same shift key can move the carriage to all three 125 130 135

case positions. By depressing the shift key the carriage is lowered to upper case, and by lifting the shift key the carriage is raised to special case.

5. Having thus described my invention what I claim and desire to secure by Letters Patents is:

1. In a type-writing machine, the combination of two type bars of substantially equal length, adjacent to one another, each provided with a type head having a plurality of types alined to print at common centers respectively, a longer type bar pivoted to vibrate between the two said type bars, and a double bend in the long bar near the type heads substantially as described.

2. In a type-writing machine, the combination of two series of type bars mounted concentrically in two circles, the type bars of one series being shorter than those of the other series and having type heads each with a plurality of characters alined to strike at common printing centers respectively, and the type bars of the other series being pivoted to vibrate to the said printing centers and having double bends near their type heads for clearance with the said shorter type bars, substantially as described.

3. In a typewriting machine, the combination, with the platen, of a series of type bars pivoted in a line about the printing point, a second series of type bars pivoted about the printing point in a line nearer than the said line of the first series, a series of type heads each bearing a plurality of characters on said second series of bars alined to print at the printing point, and double bends on said first series of bars for clearance of the said type heads.

4. In typewriting machine, the combination with the platen, of a series of type bars pivoted concentrically in the arc of a circle about the printing point, a second series of type bars pivoted concentrically in the arc of a circle of shorter radius on the same side of the printing point, a series of type heads bearing a plurality of characters on said second series of bars, alined to print at the printing point, and double bends on said first series of bars registered for clearance of the said type heads.

5. In a front strike typewriter, the combination of a type bar plate and two sets of type bars pivoted thereon, one set being longer than the other, each type bar carrying a type head with two or more type characters thereon, with the type head on the type bar directly below the printing point in line with its bar and the type heads on either side of said bar set obliquely on their bars, to all occupy a vertical position at the printing point, and double bends on the long set of type bars registered for clearance with the type heads on the short bars.

6. In a front strike typewriter, the combi-

nation of a type bar plate and two sets of type bars pivoted thereon, one set being longer than the other, each type bar carrying a type head with two or more type characters thereon, with the type head on the type bar directly above the printing point in line with its bar and the type heads on either side of said bar set obliquely on their bars, to all occupy a vertical position at the printing point, and double bends on the long set of type bars registered for clearance with the type heads on the short bars.

7. In a visible print typewriter, the combination with the platen arranged to feed crosswise the machine, of two sets of type bars, the one set longer than the other and the longer bars pivoted farther away from the printing point than the short bars, the several type bars carrying type heads each with two or more characters thereon, with the type head on the type bar which strikes to the printing point at right angles to the line of the platen feed, in line with its type bar and the type heads on either side of said bar set obliquely on their bars, to varying degrees according to the position of the respective bars, and alined to all occupy a position vertical to the line of the platen feed when their bars are brought to the printing point, and double bends on the long set of type bars formed to register with the obliquity of the type heads on the respective short bars lying between them.

8. In a typewriting machine, the combination with a platen and means for shifting it to a plurality of printing positions, of a type-bar support and two series of type-bars pivotally mounted thereon in two curved lines substantially parallel with each other at different distances from the printing point, the one series longer than the other so as to both print at the same printing point, a type-head at the free end of each type-bar comprising a central shank or means of attachment to the type-bar and a plurality of printing characters on its printing face, one character at each end thereof, the type-heads or the type-bars at either side of the printing point being mounted thereon at successively increasing degrees of obliquity so as to all assume a vertical position when brought to the printing point, and double bends in the shanks of the longer series of type-bars arranged and adapted to register, for clearance purposes, with the obliquely projecting ends of the type-heads on the shorter series of type-bars.

9. In a typewriting machine, the combination of a printing couple comprising a support for a series of type-bars and a platen, a key and connections for shifting the platen to a plurality of printing positions, two curved series of type-bars pivotally mounted on said support, each type bar provided with a type-head having a plurality of printing characters, the bars in the one series being

longer than those in the other series and having their shanks formed with double bends for clearance of the projecting heads on the adjacent bars of the said other series, key levers and operative connections between the key-levers and said type-bars.

10. In a typewriting machine, the combination of a printing couple comprising a support for a series of type-bars and a platen, a key and connections for imparting an oscillatory movement to the platen from one printing position to another, two curved series of type-bars pivotally mounted on said support, each type-bar provided with a type-head having a plurality of printing characters arranged and adapted to register with the platen in each of its printing positions, the bars in the one series being longer than those in the other series and having their shanks formed with double bends for clearance of the projecting heads on the adjacent bars of said other series, key levers and operative connections between the key-levers and said type-bars.

25 11. In a typewriting machine, the combination with a platen of a plurality of series of bars carrying type heads, the bars of the dif-

ferent series varying in length from each other, and the series of longer bars having clearance bends for the type heads on series 30 of shorter bars, substantially as described.

12. In a typewriting machine, the combination with a platen of a plurality of series of bars carrying type heads, the heads of the bars of the one series resting intermediate the 35 length of the bars of the other series, and clearance bends on the last named series for the heads on the first named series, substantially as described.

13. In a typewriting machine, the combination, with a platen, of a plurality of type bars pivoted in a plurality of curved lines about the printing point and arranged so that when at rest the type heads of certain bars will lie intermediate the lengths of the 45 bars adjacent thereto, and clearance bends in said last mentioned bars for the type heads of the first mentioned bars, substantially as described.

FREDERIC W. HILLARD.
